UNITED STATES PATENT OFFICE.

HENRY E. WARMOTH, OF STILESVILLE, INDIANA, ASSIGNOR OF ONE-THIRD TO JOHN B. JUSTICE, OF STILESVILLE, INDIANA, AND ONE-THIRD TO ROBERT T. HOLLOWELL, OF DANVILLE, INDIANA.

ADJUSTABLE WAGON-BODY END GATE.

Application filed August 21, 1923. Serial No. 653,628.

To all whom it may concern:

Be it known that I, HENRY E. WARMOTH, a citizen of the United States, residing at Stilesville, in the county of Hendricks and 5 State of Indiana, have invented a new and useful Adjustable Wagon-Body End Gate, of which the following is a specification, reference being had to the accompanying drawings and to the letters and figures of reference marked thereon.

This invention relates to an end gate for vehicle bodies that is adapted to be adjustable so as to be useful not only to retain a load in a vehicle body but to be of advantage when loading and unloading, the invention having reference more particularly to an end gate of the above-mentioned character that is designed to be readily applied to wagon bodies which may have been previously equipped with the ordinary end or tail board.

An object of the invention is to provide an improved adjustable wagon or motor truck body end gate which shall be so constructed as to be effective in retaining bulk grain or other substances, and which shall be adapted to be used either as a shoveling board when loading into the rear end of the wagon or truck body, or used as a dumping end gate.

Another object is to provide an improved end gate for wagon or motor truck bodies which shall not be costly but which shall be adapted to be readily applied to an old wagon body without the use of special tools or fastenings and without alteration of the wagon body, which may be readily removed from the wagon body when desired, and which shall be durable and economical in use.

A further object is to provide an improved wagon body end gate which shall be provided with reliable means for securing it in place and for supporting it in different adjusted positions, all to be metallic and not liable to rapid deterioration.

With the above-mentioned and other objects in view, the invention consists in an improved end gate structure for vehicles provided with novel means for hingedly supporting the upper portion of the gate and novel means for hingedly supporting the lower portion of the gate, and also improved means for securing the gate in position to retain a load; and, the inven-

tion consists further in the novel parts and 55 in the combinations and arrangements of parts as hereinafter particularly described and further defined in the accompanying claims.

Referring to the drawings,—Figure 1 is a 60 fragmentary longitudinal vertical section of a common wagon body in which the improved gate is mounted, a side elevation of the gate and its mountings being shown; Fig. 2 is a rear elevation of the improved 65 gate and end view of a wagon body to which the gate is connected; Fig. 3 is a sectional elevation approximately on the line III—III on an enlarged scale in Fig. 2; Fig. 4 is a 70 horizontal section approximately on the line IV—IV in Fig. 2; Fig. 5 is a fragmentary elevation reproducing a portion of Fig. 2 on an enlarged scale but with a number of the elements in different positions; Fig. 6 is a fragmentary top plan showing the various 75 parts seen in the preceding figure; Fig. 7 is a fragmentary vertical central section of the end gate and the wagon body longitudinally of the latter, showing the gate swung out on its upper hinge for dumping a load; 80 Fig. 8 is a vertical central section of the end gate and a portion of the wagon body longitudinally of the latter, the gate being swung out on its lower hinge; Fig. 9 is a fragmentary 85 enlarged section showing details appearing as when the gate is being swung downwards on its lower hinge; Fig. 10 is a fragmentary vertical section showing details on an enlarged scale that are not clearly 90 visible in other views; Fig. 11 is a top plan 95 of the end gate and the rearward portion of the wagon body, partially broken away, the gate being lowered as when a shoveling board is needed either for loading or unloading; and, Fig. 12 is a fragmentary perspective view of several connected parts on an enlarged scale for clearness of illustration.

Similar reference characters in the different figures of the drawings indicate corresponding elements or features of construction herein referred to in detail.

As an illustration of the type of the wagon body to which the invention may be advantageously applied, the rearward portion of a common one is shown which comprises a bottom 1 and sides 2 and 3, the inner side of one body side having two upright cleats 4

2
and 5, the opposite body side having similar cleats 6 and 7 to retain a common end beard which in the illustrations is omitted to accommodate the new end gate.

5 The new end gate includes a post or standard arranged between the cleats 4 and 5 and another post or standard arranged between the cleats 6 and 7. Each post is metallic and preferably composed of sheet metal bent 10 to the required shapes. Preferably a door sill plate 8 is secured upon the bottom 1 adjacent to the rear end thereof and so as to extend under the posts. One of the posts comprises an upright base plate 9 which is 15 arranged against the inside of the body side 2, a forward plate 10 at right angles to the base plate and a cheek plate 11 extending opposite to the base plate, and also a guide or face plate 12 supported by the cheek 20 plate at a short distance therefrom. The opposite post comprises a base plate 13, a forward plate 14, a cheek plate 15 and a face plate or guide 16, the base plate being arranged against the body side 3. The forward plates 10 and 14 are arranged on one 25 and the same plane against the rear sides of the cleats 5 and 7 respectively. One face plate or guide is secured to the cheek plate 11 preferably by means of stud rivets 17 and 30 18 adjacent to the ends thereof, the opposite face plate being likewise secured to the adjacent cheek plate by means of stud rivets 17' and 18', each rivet having a relatively 35 large body portion or spacing washer 19 or 19' thereon between the cheek plate and the face plate. A pair of bolts 20 and 21 are arranged in suitable holes in the wagon body 40 sides respectively which may have been previously bored to receive a tie rod not needed with the improved gate, the bolts extending 45 through the rearward cleats; and other bolts 22 and 23 are similarly connected to the lower portions of the body sides. Two clamp plates 24 and 25 are secured to the faces of the rearward cleats respectively by means of the upper bolts, and similar plates 24' and 25' are similarly secured by the lower bolts. The clamp plates extend forward to the forward plates 10 and 14 of the posts and have 50 flanges 26 and 27 extending to the base plates of the posts respectively to firmly clamp the posts in place. A hook-like journal bearing 28 is secured to the upper portion of the front plate 10 of one post, and a similar bearing 28' is likewise secured to the front plate of the opposite post, the bearings being on the rearward sides of the front plates, and said front plates have also ears 29 and 29' secured to the rearward sides thereof 55 below the journal-bearings respectively. The lower portions of the posts have journal-bearing members 30 and 30' secured thereto and extending rearwardly, their upper portions having slots 31 and 31' respectively to receive journals.

An improved end gate 32 composed of metal is provided and arranged to stand upright behind the face or guide plates 12 and 16, and it has side members 33 and 34 that extend behind the face or guide plates 70 so as to be between them and the adjacent cheek plates of the posts. The lower portion of the gate has a hinge bar 35 fixed thereto which has journals 36 and 37 on its opposite ends that extend into the bearing slots 31 and 31' respectively, the gate 75 preferably having also a reinforcing bar 38 fixed thereto above the hinge bar, or obviously it may be composed of a part of the hinge bar. The lower edges of the side members of the gate have notches 39 and 39' therein respectively to receive the rivets 18 and 18' respectively when the gate is in closed position and relieve the strain of the load on the journals and their bearings. 80 The lower ends of the side members have also stop projections 40 and 40' thereon respectively to engage the rivets and limit the outward movement of the gate when swung out on its upper hinge. The outer 85 side of the upper portion of the gate has shaft bearings 41 and 41' and similar bearings 42 and 42' that support shaft sections 43 and 43' to which a lever 44 is fixed, the sections constituting practically a single 90 shaft which is provided with crank pins 45 and 46 carried by arms 47 and 48 on the shaft sections respectively, the crank pins being arranged to be moved into connection 95 with the bearings 28 and 28' respectively 100 whereby to lift the gate vertically by means of the lever 44. At the top of the gate a reinforcing bar 49 is secured to the outer side thereof, the ends of the bar being turned over at right angles thereto to constitute 105 fingers 50 and 51 adapted to engage the inner sides of the cheek plates 11 and 15 respectively and prevent the spreading apart 110 of the sides of the wagon body. Two rods 52 and 53 are provided which have eyes 54 and 54' respectively that are connected with the ears 29 and 29' respectively. The rods have also hooks 55 and 55' respectively. The lower portion of the gate has clasps 56 and 56' secured thereto behind which the 115 rods are moved when crossed against the gate. At a short distance below the plane of the ears 29 and 29' base plates 57 and 57' are secured to the outer side of the gate and they have loop-shaped arms 58 and 58' 120 thereon that extend upwardly, and the arms have curved guides 59 and 59' thereon that extend inwardly each towards the other to permit the rods when released from the clasps to be swung behind the guides and 125 hang vertically, so that if then the gate be lowered on its lower hinge, the hooks on the rods shall engage the arms.

In practical use, the gate is normally supported by its lower hinge and secured in 130

place by means of the rods 52 and 53, the eyes 54 and 54' of which directly engage the adjacent portions of the gate and lock it against outward movement. In order to lower the gate, the rods are released from the clasps on the gate and they are swung behind the guides 59 and 59' respectively, after which the gate may be swung on its lower hinge and lowered until the hooks on the rods engage the arms 58 and 58' respectively. Practicing reverse operations, the gate may be readily returned to normal position and locked in place. When it is desired to dump the load, the lever 44 is drawn away from the gate to swing the crank pins 45 and 46 into connection with the bearings 28 and 28', further movement of the lever upwardly causing the crank arms to swing the gate upward until the journals 36 and 37 are released from their bearings, after which the gate may swing out until stopped by the stop devices, the locking rods hanging idly.

Having described the invention, what I claim is—

25 1. A vehicle body end gate comprising two upright posts having each an open-top journal-bearing on the upper portion thereof and an ear below the journal-bearing, the lower portion of each post having a bearing member secured thereto, each bearing member having a slot in the top thereof, an end gate having a hinge bar secured to the lower portion thereof, said bar having journals to be removably supported in said slots respectively, the gate having also side members to operate in connection with the posts, a bar secured to the upper portion of the gate and having relatively angular fingers

thereon to engage the posts, a shaft rotatively supported on the upper portion of the gate and having two crank arms and also a lever fixed thereto, the crank arms having crank pins to be connected with said journal-bearings respectively, two curved arms secured to the upper portion of the gate and having each a curved guide thereon, two clasps secured to the lower portion of the gate, and two rods having eyes connected to said ears respectively and adapted to be connected to said clasps respectively and having hooks to be connected to said curved arms respectively, the rods being adapted to be guided by said curved guides.

2. In an adjustable vehicle body end gate, the combination of two upright posts having each an open-top journal-bearing on the upper portion thereof and a bearing member secured to the lower portion of the post, each bearing member having a slot in the top thereof, an end gate having a hinge bar secured to the lower portion thereof, said bar having journals to be removably supported in said slots respectively, the gate having also side members to co-operate in connection with the posts, a bar secured to the upper portion of the gate and having relatively angular fingers thereon to engage the posts, and a shaft rotatively supported on the upper portion of the gate and having two crank arms and also a lever fixed thereto, the crank arms having crank pins to be connected with said journal-bearings respectively.

In testimony whereof, I affix my signature on the 23rd day of July 1923.

HENRY E. WARMOTH.
